Patented July 1, 1969

214,566

ANIMAL CARRIER UNIT

Elaine P. Swinney, 3700 S. Garrison St.,
Denver, Colo.

Filed May 2, 1968, Ser. No. 11,761

Term of patent 14 years

Int. Cl. D30—01

U.S. Cl. D30—1

FIGURE 1 is a perspective view of an animal carrier unit showing my new design;

FIGURE 2 is a front end elevational view of the animal carrier unit of FIGURE 1;

FIGURE 3 is a rear end elevational view of the animal carrier unit shown in FIGURE 1;

FIGURE 4 is a bottom plan view of the animal carrier unit shown in FIGURE 1;

FIGURE 5 is a top plan view of the animal carrier unit shown in FIGURE 1; and

FIGURE 6 is a side elevational view of the animal carrier unit shown in FIGURE 1.

I claim:

The ornamental design for an animal carrier unit, as shown.
